Marshall William Deutsch, Hammond, Ind.

Application January 19, 1935, Serial No. 2,578

8 Claims. (Cl. 70—9)

The invention relates to a lock key and more especially to automatically adjusted keys for tumbler locks and constitutes an improvement in the subject matter of an application for United States Letters Patent, Serial No. 732,345, filed June 25, 1934, allowed October 18, 1934; Patent No. 2,001,601, May 14, 1935.

The primary object of the invention is the provision of a key of this character, wherein tumbler mechanism is confined within the body of the key and is automatically operated for the setting thereof to effect the locking and unlocking of a tumbler lock of a construction forming the subject matter of an application for United States Letters Patent executed concurrently with this application.

Another object of the invention is the provision of a key of this character, wherein the tumbler mechanism is readily changeable through the use of an implement self-contained with said tumbler mechanism, the key body being separable so that the tumbler mechanism will be exposed and also the implement for manually actuating said tumbler mechanism and in this manner said tumbler mechanism can be set in conformity with the tumbler mechanism of the lock with which the key is useable for the actuation thereof, it being obvious that in event of the loss of a key of this kind another key of the same type may be employed as the tumbler mechanism can be set in conformity with the setting of the lost key.

A still further object of the invention is the provision of a key of this character, wherein practically unlimited variations of combinations can be had by changing the tumbler mechanism and the changing of one combination to the other is effected with dispatch and without dismantling the tumbler mechanism from the key, there being at hand within the body of the key an implement for permitting quick and easy changing of the tumbler mechanism for arriving at the desired combination, the tumbler mechanism of the key being automatically set to the combination of the lock with which it is to be used for the operation of the latter in such use.

A still further object of the invention is the provision of a key of this character, wherein the mechanism therein contained is susceptible of operating tumbler locks whose structure constitutes the subject matter of an application executed concurrently with this application, the said key mechanism being capable of operating a large number of different locks thus eliminating

the necessity of a like number of keys for the respective locks as the single key will function for the entire number of locks.

A still further object of the invention is the provision of a key of this character, which is extremely simple in its construction, thoroughly reliable and efficient in its operation, compact, strong, durable, automatic in its working through the tumbler mechanism therein contained, readily and easily adjusted for varying the combination set of the key and inexpensive to manufacture.

With these and other objects in view, the invention consists in the features of construction, combination and arrangement of parts as will be hereinafter more fully described, illustrated in the accompanying drawings, which disclose the preferred embodiment of the invention and pointed out in the claims hereunto appended.

In the accompanying drawings:

Figure 1 is a side elevation of a key constructed in accordance with the invention.

Figure 2 is a top edge view thereof.

Figure 3 is an enlarged fragmentary longitudinal sectional view through the key.

Figure 4 is a horizontal transverse sectional view taken longitudinally of the key.

Figure 5 is a fragmentary enlarged top edge view partly in section of the key.

Figure 6 is a sectional view on the line 6—6 of Figure 3 looking in the direction of the arrows.

Figure 7 is a sectional view on the line 7—7 of Figure 3 looking in the direction of the arrows.

Figure 8 is a sectional view on the line 8—8 of Figure 3 looking in the direction of the arrows.

Figure 9 is a sectional view on the line 9—9 of Figure 3 looking in the direction of the arrows.

Figure 10 is an end elevation of the key.

Figure 11 is a perspective view of the rocker push members.

Figure 12 is a perspective view of the bit push member.

Figure 13 is a perspective view of the bit adjusting implement.

Figure 14 is a perspective view for said rocker push members.

Figure 15 is a side elevation of the separable handle end section of the key.

Figure 16 is a side elevation of the separable bit end section of said key.

Similar reference characters indicate corresponding parts throughout the several views in the drawings.

Referring to the drawings in detail, the key comprises separable handle and bit end sections

A and B, respectively, the latter constituting a cylindrical body portion 10 having a reduced circular bit end 11 while the section A constitutes a closure head or cap 12 for the body portion 10 with a flattened key handle 13 formed with a hole 14 for a key chain or eulter of conventional kind (not shown).

The section B at the body portion 10 has formed at diametrically opposite points exteriorly thereof of substantially triangular shaped lateral wings 15 for matching the handle 13 of the section A, these being provided with coupling prongs 16 slidably received in companion pockets 17 formed in the handle 13 in alignment with the prongs 16 and opening through the edges of said handle for confronting the wings 15 when the sections A and B are brought together. The handle 13 has arranged therein spring acting friction latches 18 for engaging seating notches 19 therefor provided in the prongs 16 for the latching of the latter in the said handle 13 to hold the sections A and B separably connected together.

Within the cylindrical body portion 10 of the section B is a shiftable bit carrier 19' slidably fitting the said portion 10 interiorly thereof and has adjustably threaded therein a circular series of spaced adjustable bits 20 which have actuator shanks 21 working through passages 22 therefor provided longitudinally in the circular wall of the bit 11 and opening through the outer edge of the same. This carrier 19' fits about a barrel 23 of an actuator plunger having the enlarged closed striker head 24 at its outer end, the tubular barrel 23 and said head of the plunger being centered in the body portion 10 and slideable in a solid thickened portion 25 formed within the body portion 10 with the head end 24 projected into a centering stud socket 26 in the bit 11 and opening through the free end of the latter. The socket 26 in the bit 11 accommodates the centering stud within the lock constituting the subject matter of an application for patent in the United States executed concurrently herewith so that this centering stud of the lock will cause the displacement of the actuator plunger to move the same in the key for the automatic operation of the bits 20 for actuating the tumbler mechanism of said lock for unlocking purposes.

Fitted within a suitable space provided in the handle 13 of the section A is a pair of double arm rockers 27 which are supported on a pivot 28 common thereto and journaled in said handle 13. These rockers have their fulcrum arms 29 located in confronting relation to a rocker pusher member 30 and a plunger pusher member 31, respectively, these being interfitting with each other for independent sliding movement. The member 30 operates on one fulcrum arm 29 of one rocker and one fulcrum arm 29 of the other rocker 60 while the remaining fulcrum arm has one working against the pusher member 31 at one side thereof by one rocker and the other arm working against the other side of said member 31 by the other rocker and these members 30 and 31 slide reversely to each other. The member 30 has the pair of spaced leg extensions 32 which are engaged by an abutment collar 33 threaded on the inner end of the barrel 23 of the actuator plunger while the member 31 is formed with a central eye 34 accommodating the collar 33 which is slideable therein and this eye is in abutting relation to the hub 35 of the bit carrier 19'. The bit carrier 19' is tensioned by a coiled spring 36 about the barrel 23 of the plunger and seated against said carrier and against the thickened portion 25

within the body portion 10 so that the said member 30 will at all times be in contacting relation with the fulcrum arms 29 of the rockers 27 and the hub 35 of the carrier rides the collar 33 so that the member 30 will have contact at all times with the fulcrum arms 29 of the said rockers. It will be seen that the actuator plunger will be shifted when pressure is applied against its head 24, this being had by the engagement of the centering stud hereinbefore referred to of the lock. This shifting of the plunger causes the rockers 27 to turn on their pivot 28 by the engagement of the member 30 therewith and by the engagement of the member 31 with these rockers this member 31 will be shifted to move the carrier 19' 15 in the body portion 10 of the key and the bits 20 adjustably carried by this carrier will be advanced within the passages 22, that is to say, the shanks 21, and these shanks will operate upon the tumblers of the lock accordingly to the combination set of those tumblers within the lock and the bits in the keys for actuating said lock.

Formed with the head 12 of the section A of the key is an annular wall 37 having snugly and firmly fitting therein a retaining disk 38 which interfits with the members 30 and 31 for the assembling of these in the head 12 and retention therein on the separation of the section A from the section B of the key. This disk 38 has held thereby centrally of the same an implement in the form of a wrench stem 39 which releasably fits within the barrel 23 of the actuator plunger and has provided a flat faced wrench socket 40 in its outer end for accommodating the flat faced adjustment tips 41 on the bits 20, these being exposed through a retaining ring 42 fitted with the carrier 19' to retain the assembly of the bits 20, their carrier 19' and the actuator plunger including the barrel 23 and head 24 within the body portion 10 of the section B when separated from the section A. It will be seen from Figure 15 of the drawings that when the section A is separated from the section B the stem 39 is withdrawn from the head 12 with the socket 40 in the stem 39 free for engaging the tips 41 of the bits 20 which are exposed at the open end of the section B as will be apparent in Figure 16 for the adjustment of these bits 20 to change the combination setting of the same. The adjustment of the bits 20 is had through the threaded engagement thereof with the carrier 19' so that when these bits are automatically actuated certain of the same will be protruded and the others retracted within the passages 22 in conformity with the combination condition of the tumblers in the lock whereby the said bits 20 of the key through the shank ends 21 thereof will operate the tumblers in the lock for the unlocking operation of the same.

When the bits 20 of the key have been adjusted for the proper combination condition of such bits corresponding to that of the lock the sections A and B of the key are coupled together by the coupling prongs 16 engaging in the pockets 17 and latched by the friction latches 18 carried in the section A of said key.

To enable a person to identify the adjustment of the respective bits 20 of the key by the implement 39 the body portion 10 at the face of the edge adjacent to the said bits 20 has indicated thereon numerals or digits 43 numerically arranged congruous with the number of bits so that selected bits according to these digits or numerals may be identified as having been adjust-

ed or for adjustment for varying the combination of the key, this being convenient for the user of the said key.

A single key of the type before described is susceptible for serving a number of locks because the combination adjustment is of extremely wide range and thus the user of a number of locks will be required to have in his possession but a single key effective for the operation of this number of locks.

The key conforming to the construction herein set forth assures safety against unauthorized control of a lock or locks and in fact should the key fall into the hands of a person other than the rightful user thereof the lock combination of the type constituting the subject matter of the application for United States patent concurrently executed herewith may be instantly altered to avoid operation thereof by the wrong-
ful possessor of the key. Furthermore, both the key and the lock adapted to its use are susceptible of change of combinations with dispatch so as to avoid the successful use by an unauthorized person gaining possession of the key or the possession of another key of a like type while on the other hand should the rightful user suffer loss of his key there may be borrowed from another a like type of key and its bit mechanism set for use in the operation of the lock having the combination set corresponding to the lost key.

On the inner wall of the socket 26 is a guide fin 44 adapted to fit a companion groove in the centering stud of the lock hereinbefore referred to, which stud carries a frictional spring tensioned latching device to engage a seat 45 in said fin 44 so that the key will be latched within the lock when inserted therein for the operation of the same.

What is claimed is:

40 1. A lock key comprising a body having a bit portion provided with end openings, a plurality of bits arranged within the bit portion for projection through the end openings and means self-contained within the body and carried by one part thereof for guiding the other part when said parts are separated and also for effecting the change in position of the bits.

50 2. A key of the character described comprising a body having separable sections, adjustable bit mechanism within the body and accessible for adjustment on separation of the sections of said body without disassembling the said mechanism from the body and an implement self-contained within the body and carried by one section thereof for guiding the other section when bringing these together and usable on separation of the sections for altering the said bit mechanism.

3. A key of the character described comprising a body having separable sections, adjustable bit mechanism within the body and accessible for adjustment on separation of the sections of said body without disassembling the said mechanism from the body, an implement self-contained within the body and carried by one section thereof for guiding the other section when bringing these together and usable on separation of the sections for altering the said bit mechanism and means associated with said sections for retaining assemblage of said mechanism and the implement.

4. A key of the character described comprising a body having separable sections, adjustable bit mechanism within the body and accessible for adjustment on separation of the sections of said body without disassembling the said mechanism from the body, an implement self-contained within the body and carried by one section thereof for guiding the other section when bringing these together and usable on separation of the sections for altering the said bit mechanism, means associated with said sections for retaining assemblage of said mechanism and the implement and means for frictionally latching the sections of the body together.

5. A key of the character described comprising separable portions, adjustable bit mechanism carried by the sections and a guide on one of the sections for guiding the other section and usable for adjustment of the bit mechanism on separation of said sections.

6. A key of the character described comprising separable portions, adjustable bit mechanism carried by the sections, a guide on one of the sections for guiding the other section and usable for adjustment of the bit mechanism on separation of said sections and means for separably latching the sections together.

7. A key of the character described comprising a body having a separable part, bit mechanism within the body and susceptible of adjustment when the part is separated and a guide within said body for the said separable part and usable for adjustment of the bit mechanism on separation of the part.

8. A key of the character described comprising a body having a separable part, bit mechanism within the body and susceptible of adjustment when the part is separated, a guide within said body for the said separable part and usable for adjustment of the bit mechanism on separation of the part and means latching the part from separation from the body.

LEO E. DEUTSCH.
